UNITED STATES PATENT OFFICE.

BENJAMIN F. FOWLER, OF MINNEAPOLIS, MINNESOTA, ASSIGNOR OF FIVE-EIGHTHS TO
E. W. BINGENHEIMER, OF MINNEAPOLIS, MINNESOTA.

LAMP-BURNER.

964,904.

Specification of Letters Patent. Patented July 19, 1910.

Application filed November 30, 1908. Serial No. 465,018.

To all whom it may concern:

Be it known that I, BENJAMIN F. FOWLER, of Minneapolis, Hennepin county, Minnesota, have invented certain new and useful 5 Improvements in Lamp-Burners, of which the following is a specification.

My invention relates to kerosene lamps of the mantle type and the object of the invention is to provide a lamp wherein the oil 10 is vaporized before ignition, thereby preventing the discharge of smoke and products of combustion from the lamp chimney.

A further object is to provide a burner of simple, economical construction and one 15 which will provide a lamp of high candle power and great efficiency, with a comparatively small consumption of oil.

Other objects of the invention will appear from the following detailed description.

My invention consists generally in improved means for regulating the flow of air through the burner.

Further, the invention consists in means 25 for collecting the carbon from the burning wick.

Further the invention consists in improved holders for the chimney.

Further the invention consists in an im- 30 proved cone inclosing the wick.

Further the invention consists in various constructions and combinations all as hereinafter described and particularly pointed out in the claims.

5 In the accompanying drawings, forming part of this specification, Figure 1 is a vertical, sectional view of a lamp burner embodying my invention. Fig. 2 is a side view, taken on a line at right angles substantially to the section line of Fig. 1. Fig. 3 is a sectional view on the line X—X of Fig. 2. Fig. 4 is a top view of the burner. Fig. 5 is a detailed view partially in section of a modified form of cone.

5 In the drawing, 2 represents the outer tube inclosing the wick 3 and supporting a cup 4 of ordinary construction having the usual perforations. This cup is provided with a flange 5 supporting a ring 6 held in place on the cup by clips 7 and provided with a series of chimney holders, which consist of upwardly projecting arms 8, carrying spring plates 9, which are secured at points intermediate to their ends, to the up- 5 per ends of the arms 8 and are adapted to

bear at two points on the chimney. When the chimney is placed on the burner, the lower ends of the plates 9 will be forced outwardly and will bear on the base of the chimney with a yielding pressure, thereby 60 securely holding it against accidental displacement. The forcing out of the lower ends of plates 9 will have the effect of drawing the upper ends thereof inwardly to grip the chimney and hold it in place on the burner. The inner tube 10 is provided with the wick 3 and a sliding, vertically-slotted tube 11 incloses the tube 10 and has points 65 12 outwardly turned to engage with the wick. The tube 11 is provided with a rack bar 13 on one side, in engagement with a pinion 14, mounted on the wick-adjusting device 15. By the rotation of the pinion 14, the tube 11 will be raised or lowered to project or withdraw the wick.

The tubes 2 and 10 are provided with air inlet openings 16 with a wall 17 between the tubes, the tube 11 being slotted to allow for its vertical movement past the wall 17. The tube 10 has a removable cap 18 in its 80 lower end to adapt the burner for a center draft lamp. Spiders 19 are provided within the tube 10 supporting a rod 20 on the upper end of which I arrange disks 21 and 22 spaced from one another and from the 85 upper end of the tube 10 and acting as spreaders. The ring 6 is provided with an upwardly extending flange 23, which is inclosed by a cone 24 having an inwardly turned upper wall 25, terminating in a vertical flange 26. This inwardly turned wall and flange are within the lower portion of the mantle 27 when it is placed on the burner and serves to prevent side draft and the contact of the flame of the lamp with 90 the mantle. The space inclosed by the wall 25 on the upper portion of the cone forms a mixing chamber 28 where the air currents and the vapor mingle and where ignition occurs. Between the spreader 22 and the 95 flange 26 a narrow throat or passage 29 is provided.

Above the wick 3 and mounted on the tube 2 and inclosing the upper portion of the wick is an adjustable ring 30 having 100 an annular recess or depression 31 therein, which receives the burned portions of the wick when it is drawn down into the tube. The walls of the cone 24 flare outwardly 105 toward the base of the lamp and a narrow 110

passage 32 is formed between the wall 24 and the ring 30 through which the air passes into the mixing chamber. The area of this passage can be increased or decreased by 5 moving the ring 30 vertically on the tube 2 and I am thus able to regulate very nicely the volume of air passing between the ring and the cone and supplying oxygen to the wick flame. I regard this adjustable ring 10 as an important feature of my invention.

In Fig. 5 I have illustrated a modified form of cone, which I will designate by the numeral 33. This cone has a base adapted to fit on the flange 23 and has straight walls 15 to the top of the cone, instead of being inwardly curved as in the cone shown in Fig. 1. This cone 33 is designed for use without the mantle or when the lamp is used as an ordinary kerosene burner. It will be found 20 particularly serviceable when a mantle is broken and cannot, for any reason, be replaced immediately and it is desirable to use the lamp without the mantle.

I claim as my invention:—
 25 1. A lamp burner comprising a cup and ring mounted thereon and having a vertical band or flange inclosing the opening therein, inner and outer wick tubes and a wick located between them, a ring mounted on the 30 upper end of said outer wick tube, a cone having a lower edge to clasp said band and terminating with the lower portion of said band, said cone being held by frictional en-

gagement with said band and capable of vertical adjustment thereon, the wall of said cone being spaced from the ring of the outer wick tube and the vertical adjustment of the cone determining the width of this space, and the top of said cone having a central opening therein, substantially as described. 40

2. A lamp burner comprising a cup and ring mounted thereon and provided with a vertical band inclosing the opening therein, inner and outer wick tubes and a wick between them, a ring mounted on the upper 45 end of said outer wick tube, a cone having a lower edge adapted to clasp said band and supported by its frictional engagement therewith, the walls of said cone converging from its lower edge and a ring carried by the 50 said outer tube, an annular space being formed between said ring and the wall of said cone, the upper portion of said cone being inwardly turned to form an annular shoulder terminating in an upwardly projecting flange inclosing the opening provided in the top of said cone, said cone being removable from its supporting band, for the purpose specified.

In witness whereof, I have hereunto set 60 my hand this 23d day of November 1908.

BENJAMIN F. FOWLER.
